Original application December 30, 1932, Serial No.
649,567. Divided and this application July 23,
1937, Serial No. 155,237

14 Claims. (Cl. 101—300)

Our invention relates to improvements in printing presses of the bed and platen type, this application being a division of our copending application, Serial Number 649,567, filed December 5 30, 1932, Patent No. 2,091,322.

An object of the present invention is to provide an improved automatic printing press having embodied therein simple, durable and compact inking mechanism capable of highly efficient 10 operation under the various conditions encountered in the use of such presses in job work.

Another object of the invention is to provide a novel roller carriage construction which is reciprocated through balanced driving mechanism 15 designed to minimize wear and strains on the parts.

A feature of the invention resides in interposing an ink fountain between the ink plate and the position occupied by a form on the bed, and 20 in oscillating the ink fountain to apply ink to the form rollers only as they pass from the form toward the ink plate.

Another feature of the invention resides in the novel and effective association of the oscillating fountain with the throw-off mechanism of the press so that the fountain will be shifted into 25 and held in inoperative position when the impression is thrown off.

A further object of the invention is to provide, 30 in connection with the roller carriage, a frame for distributing rollers, which frame is swingable to give access to the form rollers at the front of the carriage.

Another object of the invention is to provide 35 for the ready removal of the form rollers from the carriage, and for the ready adjustment of said rollers in the carriage, whereby, in a single guided movement, each form roller may be shifted toward or from the plane of the form and inking plate and, simultaneously, toward or 40 from the periphery of its respective distributing roller.

A feature of the invention resides in swinging 45 the inking plate out of the inking plane to lend access thereto and to the form rollers at the rear of the roller carriage.

A still further object of the invention is to provide for the intermittent oscillation of the inking plate, to present the same in different angular relations with respect to the form, whereby uniformity in the distribution of ink is 50 promoted.

With the foregoing and other objects in view, 55 which will appear in the following description, the invention resides in the novel combination

and arrangement of parts and in the details of construction hereinafter described and claimed.

In the drawings, Figs. 1 and 2 are perspective views illustrating a form of our improved printing press construction; Fig. 3 is an elevational view of the structure shown in Figs. 1 and 2, the view being taken from the left side of the press; Fig. 4 is a rear elevational view of the structure shown in Figs. 1, 2 and 3; Figs. 5 and 6 are vertical central sectional views of said structure 10 taken in opposite directions; Fig. 7 is a vertical sectional view taken on the line 7—7 of Fig. 5; Fig. 8 is a detail view showing, particularly, the gearing and cam assembly at the right side of the illustrated press structure; Fig. 9 is a vertical, central sectional view taken through the bed of the press and illustrates the construction and relative arrangement of the roller carriage rails, the oscillating ink fountain, the swingable ink plate, the carriage blocks and form rollers 20 and distributing rider rolls carried thereby; Fig. 10 is a detail view in section taken as on the line 10—10 of Fig. 9; Fig. 11 is a perspective view illustrating one of the carriage blocks and also showing the construction of the adjustable cup 25 bearings for the form rollers; Fig. 12 is a sectional view in detail, the same being taken as on the line 12—12 of Fig. 9; Fig. 13 is a detail perspective view of one of the cup bearings for the form rollers; Figs. 14, 15, 16 and 17 are diagrammatic views illustrating the action of the mechanisms employed to oscillate the ink fountain and to rotate the fountain roll, and Figs. 18, 19 and 20 are detail views showing the oscillating inking plate, its swingable mounting and the means 30 employed in oscillating said plate, Fig. 18 being a front elevational view, Fig. 19 a sectional view taken on the line 19—19 of Fig. 18, and Fig. 20 a view similar to Fig. 19 showing the parts of the plate oscillating mechanism in positions other 35 than those shown in Fig. 19.

Reference being had to the drawings, wherein similar parts throughout the several views are designated by similar reference characters, it will be noted that the illustrated press structure 45 includes right and left side frames 30, 31 connected by cross stays 32. A crank-shaft 33 journaled in the side frames 30, 31 carries a fly wheel 34 at one end thereof and to this is keyed a pinion 35 (Figs. 1 and 8), which meshes with a 50 gear cam wheel 36 fixed to a shaft 37 journaled in said side frames 30, 31. Trunnioned in the side frames 30, 31 is a platen rocker 38 carrying a platen 39. Secured to a trunnion 40 (Fig. 8) of said platen rocker 38 is a rocker arm 41 having 55

a cam roller 42 thereon which travels in the cam 43 of the gear cam wheel 36, said rocker arm 41 serving to oscillate said platen rocker 38 and the platen 39 carried thereby. Back of the side frames 30, 31 is a bed 44 having a form receiving recess 45 therein and having legs 46 pivoted on a bed shaft 47 mounted at its ends in the lower rear portions of the side frames 30, 31. Journaled in ears 48 projecting rearwardly from the bed 44 is a back shaft 49 to the ends of which are connected side arms 50, 51, the former being connected with a crank wheel 52 on the shaft 37 and the latter with the gear cam wheel 36 also on said shaft 37. Power applied to the crank shaft 33, as through a pulley 53 (Fig. 4) thereon, causes the platen 39 to tip back and forth from open position (Fig. 6) to impression position (Fig. 3) and causes a relative movement of the bed 44, bringing a form therein against the platen 39 in its impression position and substantially retracting the bed 44 from the platen 39 in the open position of the latter.

Rails 54 secured to the sides of the bed 44 guide carriage blocks 55 up and down thereon. These blocks 55 support inking rollers 56 which in their reciprocating cycle, contact with a form in the bed 44 and with an inking plate 57 between the rails 54 and also with the fountain roll 58 of an oscillating ink fountain 59 disposed between said bed and inking plate. The carriage blocks 55 are reciprocated in unison by similar mechanisms at either side of the press, which include bell-crank 60 keyed to the opposite ends of a shaft 61 journaled in the side frames 30, 31, and which further include rods 62 and links 63, the rods 62 connecting the bed with said bell cranks 60 and the links 63 connecting said bell cranks with said blocks 55. Due to the arrangement of the bell cranks 60, as shown, the connections between them and said links 63 are constantly disposed substantially in the reciprocal plane of the carriage blocks 55, the result being that forces acting on the carriage blocks 55, through the links 63, are at all times exerted in directions substantially parallel with the rails 54 upon which said blocks ride. This feature, is shown in Figs. 3 and 5, where the blocks occupy extreme positions and the links 63, in both positions of said blocks, occupy positions substantially paralleling the rails 54. With said links 63 thus disposed at all times with respect to the rails 54, it will be readily understood that lateral thrusts of the carriage blocks 55 against their rails are practically eliminated and that said blocks will move freely up and down on said rails without binding.

Counterbalancing the weight of the roller carriage blocks 55 and the rollers 56 carried thereby, is a compression spring 64 (Fig. 6). This spring encircles a rod 65 pivotally connected at its forward end to a cam 66 on the shaft 61 and slidably mounted at its rear portion in a bracket 67 secured to a cross stay 32 between the side frames 30 and 31. The forward end of the spring 64 abuts against a collar 68 on rod 65 while the rear end of said spring abuts against the bracket 67. The cam 66 constitutes an arm for resisting, through spring 64, the rotation of shaft 61 in a direction to lower the carriage blocks 55, the strength of said spring being such as to substantially balance the carriage blocks 55 and the inking rollers carried thereby. In this construction, the carriage blocks 55 with their rollers 56 are easily moved up and down the rails 54 without strain or undue wear upon the parts.

75 Provision is made for throwing off the press or,

in other words, for shortening the normal forward throw of the bed 44 and thereby preventing the form in the bed from contacting with the platen 39 in its impression position. To this end, the back-shaft 49 is formed at its extremities with eccentric studs 85 (dotted lines, Figs. 14-17) to which the rear ends of the side arms 50, 51 are pivotally connected. Secured to the back-shaft 49 for rocking the same, is an arm 86 (Figs. 3 and 7) having pivoted thereto a depending link 87. At its lower end, this link 87 is connected through a pivot pin 88 with the forward end of an arm 89 (Figs. 2 and 3), the rearward end of which is pivoted to an upright bracket 90 secured to a foot of the side frame 31. Said arm 89 is normally held against pivoting on the bracket 90 and in position, wherein the axis of the pivot pin 88 coincides with the axis of the bed shaft 47. In this relation of said parts, the back shaft 49 is held against rotation as the bed 44 rocks back and forth and in such angular position in its bearings that the eccentric studs 85 are properly disposed to cause the form in the bed to contact with the platen 39 in the impression positions of bed and platen. The means for holding the arm 89 in its normal position (Fig. 2) consists of a suspension link 91, jointed medially, as at 92. This suspension link 91 is pivoted at its lower end to the arm 89 by means of the pivot pin 88 through which said arm is connected to the depending link 87, the upper end of said suspension link 91 being pivoted to the tip of the upright bracket 90. Through said suspension link 91, the forward end of the pivoted arm 89 is elevated to thrust the link 87 upwardly and thus rock the arm 86 and turn the back shaft 49 sufficiently to prevent the bed from closing against the platen. Operating to break the jointed suspension link 91, and thus swing the arm 89, is a hand lever 93 pivoted between its extremities to a bracket 94 on the side frame 31, the lower end of said lever 93 being connected by means of a tie bar 95 with an arm 96 issuing from the upper member of the jointed link 91. Upon swinging the upper end of the hand lever 93 rearwardly, the link 91 is broken at the joint 92 therein and the train of parts, consisting of the pivoted arm 89, depending link 87 and rock arm 86, is actuated to rock the back shaft 49 and throw off the impression. The impression is thrown on again by swinging the hand lever 93 back and thus restoring the back shaft 49 to its normal position. As the jointed suspension link 91 reassumes its extended position, the axis at the joint 92 thereof passes slightly past center at which point the lower extremity of the upper member of said link engages a stop lug 97 on the pivoted arm 89. In this relation of parts, the jointed link 91 is locked against being broken, except through a pull on the tie-bar 95, the pivoted arm 89 being thus rigidly held against pivotal movement and the back shaft 49, in turn, firmly held against rotation in the rocking bed. The hand lever 93 is not only operated by hand, but is also operated automatically, as will later appear, for the purpose of throwing off the impression when the automatic sheet feeding mechanism, hereinafter described, fails to grasp a sheet and for the purpose of throwing on the impression when said feeding mechanism again takes a sheet.

The guide rails 54 for the ink roller carriage blocks 55 consist of bars suitably secured flatwise to the sides of the bed 44, each of the bars being beveled at both edges to form opposed V-shaped ways 98.

The carriage blocks 55, constituting a roller

carriage, ride up and down on said guide rails 54 and in their reciprocating cycle bring the composition form rollers 56 into contact with a form in the bed 44 and with the fountain roll 58 of the oscillating inking fountain 59 carried by said rails 54 above the bed, and also bring said composition rollers 56 into contact with the inking plate 57 carried by said rails 54 above said inking fountain 59. On the upward stroke of the carriage blocks 55 the ink rollers 56 engage the then projected fountain roll 58. In the final stage of said upward stroke of said carriage blocks, and also during the initial stage of their downward stroke, the ink rollers 56 contact with the inking plate 57 effecting a distribution of ink thereon and on said rollers 56. As the carriage blocks 55 descend and pass the form in the bed 44, the ink rollers 56 contact with and ink the form.

The carriage blocks 55 are elongated structures, each including a web-like body and front and rear bearings 9 (Fig. 11), which correspond with and ride the opposed V-shaped ways 98 of its respective carriage rail 54. Each carriage block 55 further includes a forwardly projecting frame plate 100, the two frame plates of the two blocks serving to support the form rollers 56. Hinged frames 101 (Fig. 9), one for each frame plate 100, support ink distributing rollers 102, which ride the form rollers 56. Each hinged frame is of bar-like construction pivoted at one extremity to the lower end of its respective frame plate 100 and provided at its other extremity with a locking head 104. Normally, these hinged frames 101 are closed upon the frame plates 100 of the carriage blocks 55, the head 104 of each hinged frame being releasably engaged by a latch 105 pivoted at the upper end of its respective frame plate 100.

The ink distributing rollers 102 (Figs. 7, 9 and 10) are of the vibrating type, the threaded ends of the shafts 106 thereof being threaded in one of the hinged frames 101 in bosses 107, while the opposite ends of said shafts are journaled in the other hinged frame 101 in bosses 108. Said shafts 106, at said latter ends thereof, are provided with gears 109, meshing with idler gears 110 mounted on the frame plate 100 of the corresponding carriage block 55, said idler gears 110 being also in mesh with a rack bar 111 secured to the rail 54 upon which said block rides. The bosses 107, 108 on the hinged frames 101 enter guiding recesses 112 (Figs. 9 and 11) in the frame plates 100 when said frames 101 are closed upon said frame plates with the result that the vibrating distributor rollers 102 always have the same relative disposition in the roller carriage when the hinged frames 101 are latched in place. The four composition form rollers 56 are arranged in pairs, the two rollers of one pair being adapted to be engaged by one of the vibrating distributor rollers 102 and the two rollers of the other pair being adapted to be engaged by the other vibrating distributor roller. All of said form rollers 56 are adapted to engage the inking plate 57 and the form in the bed 44, said rollers 56 being adjustably and removably mounted on the frame plates 100 of the carriage blocks 55, the mode of mounting being the same in each instance. Referring to Figs. 9 and 11 and to the companion views on the same sheet, it will be seen that each inking roller 56 has roller bearings 113 secured to the opposite ends of its shaft 114. These roller bearings 113 are removably seated in cup bearings 115, each of which comprises a disk-like head 116 and a flange 117, semi-circu-

lar in form, issuing from said head. On this head 116, at the side thereof opposite the flange 117, is a curved rib 118, which fits in a curved groove 119 (Fig. 11) in one of the frame plates 100, said rib 118 and head 116 being formed with a threaded bore 120 to receive the threaded end of a fastening bolt 121 (Fig. 12) passing through a curved slot 122 formed in the frame plate 100 and communicating with the curved groove 119 in which the rib 118 is disposed. With the cup bearing 115 secured in place by its fastening bolt 121, the lower portion of the flange 117 slightly underreaches the roller bearing 113 placed therein, said flange in conjunction with a keeper 123 serving firmly to hold the roller bearing 113 in place. Said keeper 123 consists of a pin with a right angular bend therein, one reach of the pin constituting a stem 124 which is slidably and rotatably mounted in a bore 125 in the head 116, the other reach of said pin constituting a finger 126 adapted to overreach the roller bearing 113 in cup bearing 115. A spring 127 acting on the stem 124 of the keeper causes the finger 126 to engage said roller bearing 113 yieldingly, said spring being interposed between the head 116 of the cup bearing and a pintle 128 passing through said stem 124 of the keeper 123. The head 116 is notched as at 129 (Fig. 13) to receive the finger 126 and thus allow it to engage and hold the roller bearing 113 seated in the cup bearing 115. At one side of this recess 129, the head 116 is machined to form a cam surface 130 upon which the finger 126 rides, when it is turned (Figs. 9 and 11) to free the roller bearing 113. In thus turning said finger 126, the cooperation thereof with said cam surface 130 results in readily sliding the stem 124 in the head 116 against the action of the keeper spring 127.

The curved grooves 119 for the companion cup bearings 115 of each pair of inking form rollers 56 are oppositely disposed, as shown in Fig. 11 and provide for adjustments of said cup bearings, whereby the form rollers 56 carried thereby may be shifted toward or from their respective ink distributing roller 102 and the plane common to the inking plate 57 and the form. These adjustments are readily made to compensate for expansion and contraction in the form rollers 56, the ease of adjustment being facilitated due to the form and arrangement of the grooves 119, whereby the movement of an inking roller 56 toward its respective distributor roller 102 is effected simultaneously with a corresponding appropriate movement of such inking roller 56 toward the plane of the inking plate 57.

In addition to the vibrating distributor rollers 102, the hinged frames 101 carry idler distributing rollers 131, 132 (Figs. 9 and 10), which ride certain of the form rollers 56. Roller 131 is journaled at its ends in pins 133 slidably mounted in bearings 134 secured to the hinged frame bars 101. These bearings are so located on said frame bars 101 that the roller 131 lies between the lower roller of the upper pair of inking rollers 56 and the upper roller of the lower pair of inking rollers 56, when the hinged frame bars 101 are closed upon the frame plates 100. Said distributing roller 131, in such position, contacts yieldingly with said inking rollers, due to the action of expansion springs 135 which encircle the pins 133 and react against the bearings 134. Distributing roller 132 is arranged to engage the uppermost inking roller 56 and is journaled at its ends in clips 136 pivoted to the hinged frame arms 101 on clamping screws 137, which are released to permit of the adjustment of said roller 135.

132 and thereafter tightened to secure it in adjusted position.

In providing the upper vibrating roller 102 for the two form rollers 56 of the upper pair thereof 5 and the lower vibrating roller 102 for the two form rollers 56 of the lower pair, and in further providing the rider roller 131 for the lower form roller 56 of the upper pair and for the upper form roller 56 of the lower pair, the ink on said rollers 10 is effectively broken up, without interruption, through the entire train thereof.

In mounting the ink distributing rollers 102, 131 and 132 on the hinged frame arms 101, said rollers are easily swung forwardly away from the 15 form rollers 56 to facilitate the cleaning of all of said rollers. In further facilitating the cleansing of the form rollers 56, the inking plate 57 is adapted to be swung rearwardly from its normal position (Fig. 6), into a retracted position such as 20 that shown in Fig. 9 and thus give access to said rollers 56 from the rear as well as from the front.

The oscillating ink fountain (Fig. 9), indicated in its entirety at 59, includes end frame members 25 138 and the fountain feed roll 58 journaled at its ends in said end frame members. This ink fountain 59 further includes a back wall 139, a plate 140 secured along its upper edge to said wall 139, and thumb screws 141 threaded in said 30 wall for holding the lower marginal portion of said plate 140 more or less closely positioned with respect to the fountain feed roll 58. The end frame members 138 are secured to brackets 142 pivoted on studs 143 threaded in the guide rails 54.

35 A horizontally disposed U-shaped extension 144 (Fig. 4) is attached to the ink fountain 59, one branch of said extension being suitably secured to an end wall 138 of said fountain. A leg 145 secured to said extension and extending rearwardly therefrom and thence downwardly is supplied at its lower extremity with a roller 146 which bears upon a track 147 (Fig. 3). This track 147 is pivoted at its forward end to the side arm 50 at the left side of the unit, said track at the rear end thereof being beveled as at 148, the beveled portion resting upon a pin 149 mounted on a cap piece 150 secured to the end of the back shaft 49. Through said side arm 50 and track 147, the inking fountain 59 is oscillated and normally caused to swing forward and backward, whereby the fountain feed roll 58 occupies position for inking the form rollers 56 during the upward movement of said rollers, but is otherwise disposed in a retracted position to avoid contact with said inking rollers 56. This oscillation of the ink fountain, through leg 145, is effected by the angular movement of the side arm 50 combined with the angular movement of the track 147 relative to said side arm. Referring to Figs. 14 to 17 inclusive, which illustrate diagrammatically various relative positions assumed by the ink fountain 59, form rollers 56, side arm 50 and track 147, it will be observed that, as the form rollers 56 ascend toward the fountain feed roll 58, the side arm 50 elevates the forward end of the track 147 and at the same time causes the elevation of the rear end of said track by sliding the beveled portion 148 thereof upon the bearing pin 149. By reason of this compound movement the track 147 is 70 elevated sufficiently to cause the rocking of the ink fountain 59 into a forwardly projected position in which the fountain feed roll 58 engages the ascending form rollers 56. As said form rollers 56 descend, the change in angularity of 75 the side arm 50 lowers the forward end of track

147 and simultaneously slides the beveled rear portion 148 thereof forwardly upon the bearing pin 149, such movement of said parts resulting in the lowering of the track 147 sufficiently to allow the ink fountain 59 to swing backward and thereby retract the fountain feed roll 58 in time to avoid engagement with the descending form rollers 56. 5

The normal oscillation of the ink fountain 59, above described, is interrupted when the throw-off mechanism of the unit is operated to shorten the forward throw of the bed and prevent the taking of an impression. In this connection and having reference to Figs. 3 and 15, it will be seen that the ink fountain 59 will be retracted upon 15 a counter-clockwise movement of the back shaft 49 as a consequence of the upward throw-off thrust of the link 81. Upon such rotation of the back shaft 49 the cap 150, which is secured thereto, turns with the said shaft and as a result 20 moves the bearing pin 149 rearwardly beneath the beveled portion 148 of the track 147, thus lowering said track. The fountain 59, supported by the track, is thereby caused to be retracted, if not then so disposed, and to remain in retracted position, wherein the fountain feed roll 58 25 clears the form rollers 56.

The fountain feed roll 58 is rotated step by step to present freshly inked portions thereof to the form rollers 56 by mechanism, best seen in Figs. 2, 30 4 and 7, which includes a drive shaft 151 journaled in the branches of the U-shaped fountain extension 144. Secured to this drive shaft 151 is a gear 152 which meshes with a gear 153 on the fountain roller shaft 154. A ratchet wheel 155 35 also secured to said drive shaft 151 is turned by means of a pawl 156 carried on one arm of a bell crank 157 rockably mounted on said driving shaft 151, the other end of said bell crank being connected through a link 158 with the side arm 50 40 at the left side of the machine, said link serving to impart a rocking movement to said bell crank 157. To provide for the turning of the fountain drive shaft 154 more or less each time the bell crank 157 is actuated, we employ a shroud 159 45 consisting of a disk rockably mounted on the drive shaft 151, said disk having an offset cam surface 160 with which the pawl 156 may be engaged to prevent its engagement with the teeth of the ratchet 155 during a part of the rocking movement of the bell crank 157. This shroud 159 is 50 adjustably held in various selected positions by means of a brace 161 which is pivotally secured at its lower end to the fountain extension 144 and slotted at its upper portion to pivotally and slidably receive a clamping bolt 162 carried by an arm 163 projecting from the disk-like body of the shroud 159. With said shroud 159 positioned in selected angular relation on the shaft 151 and held in such position by the brace 161, the extent 60 of rotation of the fountain roll 58 to accord with any particular requirement is secured. A hand wheel 164 on shaft 151 is supplied for manually turning the fountain roll 58 at such time as may be desired. 65

The inking plate 57, which is rectangular in form, is mounted on a back-frame 165 of similar form, said back-frame presenting a supporting surface against which the back of said plate 57 bears (Fig. 9). This back-frame 165 is hingedly supported upon the rails 54, ears 166, provided at the lower corners of said back-frame, being pivoted on studs 167 threaded into said rails. A prop 168, depending from a shaft 169 journaled in ears on the back-frame 165, has a footing, nor- 75

mally, on the upper end of a brace 170 (Figs. 3 and 9) issuing upwardly and rearwardly from the bed 44. Through the brace 170, prop 168 and back-frame 165, the inking plate 57 is releasably held in operative position, the back-frame 165 occupying position with the upper margin thereof abutting front stops 171 secured to the rails 54.

The inking plate 57 oscillates on the back-plate 165, the former having a central boss 172 (Fig 9) journaled in a central bearing 173 formed on the latter. Mechanism, now to be described, automatically swings the inking plate 57 angularly from one position to another and back again, whereby, upon one cycle of the form rollers 56, said inking plate will occupy one position angularly of said form rollers and, upon the next cycle, will occupy another position angularly of said rollers, the shifting of the inking plate back and forth from one position to the other causing 20 the ink on the rollers 56 and plate 57 to be effectively broken up and distributed thereon. Disposed between the rail 54 and the adjacent ear 166 of the back-frame 165, at the right side of the press, is a cam 174 (Figs. 18, 19 and 20) and 25 a ratchet wheel 175 axially interconnected therewith, said cam and ratchet wheel being mounted to turn on the stud 167 supporting said ear 166. Cooperating with the ratchet wheel 175 is a pawl 176, the same being pivoted on the adjacent end 30 frame 138 of the oscillating ink fountain 59. The cam 174 has alternating high and low portions, the teeth in the ratchet wheel 175 being the same in number as said portions of said cam. A thrust-rod 177, guided in a bracket 178 issuing 35 from the back-plate 165, is connected at its upper end through a lug 179 with the upper right hand corner of the inking plate 57, the lower end of said thrust rod 177 being equipped with a cam follower 180 which rides the cam 174. As previously explained, the oscillating ink fountain 59 is swung forward on each cycle of the form rollers 56 to bring the fountain roll 58 in contact with said form rollers 56 as the latter, in their ascent, approach the inking plate 57. Such forward swing of the inking fountain, causes the pawl 176 to turn the ratchet wheel 175 and also the cam 174 with which said ratchet wheel is connected. Upon each step of the cam 174, the inking plate 57 is swung into one or the other 40 of the two positions indicated in Fig. 18, said plate being caused to take the position shown in solid lines, when a high portion of the cam 174 comes into play and being caused to take the position shown in dotted lines when a low portion 45 of said cam comes into play. The shifting of the inking plate 57 into said solid line position is accomplished by the coaction of a high portion of the cam 174 and the thrust-rod 177, while the shifting of said plate, into said dotted line position, is accomplished by means of a spring 181 stretched between the lug 179 on said inking plate 57 and the guide bracket 178 on the back-plate 165, such spring serving yieldingly to keep the cam follower 180 in contact with the cam 174.

50 Mounted on the shaft 61 at the right side of the press is a cam assembly (Figs. 1 and 8) consisting of a sleeve 198 journaled on said shaft and of cams 202 and 203 keyed to said sleeve. This cam assembly is driven from the gear cam wheel 36 through a reduction idler consisting of a large gear 204 and a smaller gear 205, the former being in mesh with the teeth of the gear cam wheel 36 and the latter in mesh with a gear 206 keyed to said sleeve 198.

55 Power is derived through said cam assembly

for driving the moving parts of a sheet feeding mechanism B generally of the construction disclosed in letters patent of the United States Nos. 1,472,656 and 1,592,635 which matured from applications filed by us, the same being more especially like that of Patent 1,592,635 in the detailed construction of the head member. This feeding mechanism includes an oscillating feed arm 231 having suction grips 232 thereon which take sheets to the platen 39 from a suitably supported stock pile and carry said sheets, edge foremost, depositing them in desired position on the platen.

Further included in said feeding mechanism B is a tubular standard 233 (Fig. 1) mounted at the right side of the press in bearings 234 formed integrally with a gear guard 190. Supported at the upper end of the standard 233 and extending inwardly over the bed 44 is a horizontally disposed head bearing 235 in which an eccentric bushing 236 is rockably mounted, the same being provided at its outer end with a rocker-disk 237. Mounted in said bushing 236 is a rock shaft 238 which at its inner end carries the feed arm 231 and to the outer end of which is secured a rocker arm 240. A rod 241 connects the rocker-disk 237 with the free end of a lever 242, while a similar rod 243 connects the rocker-arm 240 with the free end of a lever 219. These levers 219 and 242 are pivotally mounted on a shaft 221 supported in bosses 222 on the side frames 30, 31. Said levers 219 and 242 are operated, respectively, by the cams 203 and 202 of the cam assembly, each lever having a roller, as at 244, which rides its respective cam. Through cam 203, lever 219, rod 243, and rocker-arm 240, the feed arm 231 is oscillated in accord with the rocking movement of the platen, whereby a sheet from a stock pile is fed to the platen each time it opens, the suction grips 232 and feed arm 231 safely clearing the platen 39 in the co-ordinated cycles of movement of feed arm and platen. Through cam 202, lever 242, rod 241, and eccentric bushing 236, the rock-shaft 238 is shifted to increase and diminish the reach of the feed arm 231 for facilitating the taking of sheets from the stock pile and placing of sheets on the platen 39 and the clearing of the platen and suction grips 232 during the oscillating movements of said feed arm 231 and platen 39. Suction is created in the grips 232, by means of a suction pump 227 of conventional construction, the piston rod 228 of the pump being connected with a crank 229 on the fly wheel shaft 33 and the body of said pump being pivotally supported on a beam 230 carried at its ends by the side frames 30, 31. Said pump is connected at its suction side with said grips 232 through a tube 245, pipe 246, the tubular standard 233, the hollow feed arm 231, a tube 247 connecting the hollow standard 233 with the hollow feed arm 231, and tubes 248 leading from the grips 232 to said feed arm 231, said pipe 246 being fitted with a valve 249 (Fig. 4), suitably operated manually to cut off suction in the line to said suction grips 232. The tube 247 takes off from the hollow standard 233 above a self-seating ball valve (not shown) for obstructing and clearing the passageway in said standard and beneath a self-seating ball valve 253 (Fig. 2) for admitting and barring the entrance of air to said passageway. These ball valves are unseated by a lever 254 (Fig. 1), which is automatically actuated to effect suction at the grips 232 in the sheet receiving position thereof and to destroy such suction in the selected sheet depositing position of said grips. No 75

claim being made herein to the said valves or their actuating mechanism per se, we have not deemed it necessary to illustrate and describe the same in detail, particularly in view of the disclosure in Patent No. 1,592,635.

As the bed 44 assumes printing position (Fig. 3), its superstructure, including the rails 54 and ink plate 57, swings forward, passing closely beneath the head bearing 235 of the feeding mechanism B into a position over the center of the machine, the feed arm 231 being formed with a bend therein to clear said superstructure. This relation of said parts contributes to the compactness and to the balancing of the press structure.

Means are provided for automatically "throwing off" the press and thus preventing the taking of an impression when the suction grips 232 fail to grasp a sheet at the stock pile, such means including a piston 255 (Fig. 8) in the standard 233 and a train of connections, now to be described, which act upon the throw-off lever 93. Pivoted between its ends on a bracket 256 issuing from the side frame 30, is a lever 257 having a weight 258 attached to its forward end, said weighted end of said lever being connected through a connecting rod 259 with the piston 255 and normally held against being swung downward by the sustaining action of said piston. The rear end of the lever 257 is connected through a link 260 with an arm 261 on a rock-shaft 262 mounted transversely of the legs 46 of the bed 44 in bearings secured to said legs, the connection between the link 260 and lever 257 being coincident with the axis of the bed shaft 47 in the normal position of said lever 257. On the rock-shaft 262 is a second arm 263 (Fig. 3) having a pin 264 at the end thereof normally freely movable back and forth in a slot 265 cut in a link 266 which forms a connecting element between the bed 44 and the throw-off lever 93. This link 266 has a second slot 267 therein and is notched upwardly as at 268 (Fig. 2), between the ends thereof to receive a pin 269 (Fig. 3) in the throw-off lever 93, said pin serving to support the forward end of said link 266 and, when normally engaged in said notch 268, serving to pivotally connect said link 266 with said lever 93. Supporting the rear end of the link 266 is a flanged stud 270 which is secured to a leg 46 of the bed 44 and which normally slides back and forth beneath said link 266. When suction in the hollow standard 233 is impaired, as by the failure of the suction grips 232 to grasp a sheet at the stock pile or, as by the manual closing of the valve 249 in pipe 246, the piston 255 in standard 233 fails to support the weighted end of the lever 257, with the result that said lever 257 acts to turn the rock-shaft 262 and swing the arm 263 so that the pin 264 on said arm enters a notch 271 cut downwardly in link 266 at the rear end of the slot 265 along which said pin normally freely passes. With said pin 264 engaged in said notch 271, the link 266 is moved with the bed 44 and, in turn, imparts such movement to the throw-off lever 93 through which the previously described throw-off mechanism is operated to turn the back shaft 49 and prevent the bed from fully completing its impression throw. Thus, upon each impression throw of the bed 44 and until suction is resumed in the standard 233, the throw-off lever 93 is automatically shifted to prevent the taking of an impression. Carried by the throw-off lever 93 (Fig. 2) is a trip rod 272, the same being connected at

its upper end with a hand piece 273. The lower end of said rod 272 is bent inward providing a finger 274 which extends through a slot 275 in said lever 93 and beneath the link 266. Upon operating the hand piece 273 and thereby lifting the trip rod 272, said finger 274 engages and lifts the link 266 so that the pin 269 in the lever 93 occupies position in the slot 267 in said link rather than in the notch 268 branching upwardly from said slot. With the link 266 thus elevated by the trip rod 272, the connection between said link and the throw-off lever 93 becomes a sliding connection rather than a pivotal connection with the result that the link 266 reciprocates independently of the hand lever 93. The hand lever 93 being thus free from the link 266, it may be operated at will to throw on or throw off the impression.

The cam rollers 244 of the cam levers 219 and 242 are maintained in contact with the cams 202 and 201 by means of expansion springs 302 (Fig. 8). Each of said cam levers is integrally formed with a depending arm 303 having a socket therein in which one end of a rod 304 is received, the other end of said rod being slidably supported in a lug 305 issuing from the bracket 256. Encircling each of these rods 304 is one of said expansion springs 302, each spring abutting against the lug 305 at one end and at its other end against a washer 306 fixed to its respective rod 304. Thus, the springs 302, operating through the arms 303 and the cam levers 219 and 242, yieldingly hold said cam rollers 244 in contact with said cams 202 and 203.

Changes in the specific form of our invention, as herein disclosed, may be made within the scope of what is claimed, without departing from the spirit of our invention.

Having described our invention, what we claim as new and desire to protect by Letters Patent is:

1. Inking mechanism for a printing press having a pivotally supported bed, a platen, a side rod connected with the bed for rocking it toward and from the platen, an eccentric embodied in the connection between said rod and bed, grips for feeding sheets to the platen to be printed, and means actuated through the grips, in the absence of a sheet in their grasp, for turning the eccentric out of impression effecting position and, in the presence of a sheet, for turning said eccentric into impression effecting position, said inking mechanism comprising form rollers, an ink plate, and an oscillatory ink fountain having a feed roll, the fountain being interposed between the ink plate and the position on the bed occupied by a form, means for moving the form rollers back and forth over the ink plate and the form on the bed, and means for advancing the ink fountain to locate the feed roll thereof in position to be engaged by the form rollers in their travel from the form to said plate and for retracting said fountain to withdraw said feed roll into position clear of said form rollers on their return from said plate to said form, and means associated with said side rod and eccentric for rendering said fountain moving means inoperative to advance the fountain, when said eccentric is turned out of impression effecting position.

2. Inking mechanism for a printing press having a platen, a bed, a member connected with the bed, means including said member for relatively moving said bed and platen to bring them together into printing relation and to separate the same, an eccentric embodied in the connection between said member and bed, means for

- turning the eccentric out of and back into impression effecting position, said inking mechanism comprising form rollers, an ink plate and a movable ink fountain having a feed roll, the fountain 5 being interposed between the ink plate and the position on the bed occupied by a form, means for moving the form rollers back and forth over the ink plate and the form on the bed, and means for advancing the ink fountain to locate the feed 10 roll thereof in position to be engaged by the form rollers in their travel from the form to said plate and for retracting said fountain to withdraw said feed roll into position clear of said form rollers on their return from said plate to said form, and 15 means operating, when the eccentric is turned out of impression effecting position, to render the fountain moving means inoperative to advance said fountain. 15
3. Inking mechanism for a printing press having a bed, a platen, means for effecting a relative movement between said bed and platen to bring them together into printing relation and to separate the same, said inking mechanism comprising an ink plate having a mounting therefor 20 supported on the bed, a roller carriage reciprocably mounted on the bed, form rollers mounted on the carriage, means for reciprocating the carriage to engage the form rollers with a form on the bed and with said plate, the ink plate being movable on its mounting out of the inking plane to lend access to said plate and also to the form rollers at the sides thereof normally in engagement with said plate. 25
4. Inking mechanism for a printing press having a bed and a platen, means for effecting a relative movement of bed and platen to bring them together into printing relation and to separate the same, said mechanism comprising an ink plate hingedly mounted on the bed, a roller carriage reciprocably mounted on said bed, form rollers mounted on the carriage, means for reciprocating the carriage to engage the form rollers with a form on the bed and with said plate, a frame hingedly mounted on the roller carriage, ink distributing rollers mounted on the frame and normally riding said form rollers, said frame and ink plate being oppositely swingable on their respective mountings to afford access to the ink distributing rollers on the frame and to the inking plate and to both sides of the form rollers. 30
5. Inking mechanism for a printing press having a bed and platen, means for effecting a relative movement between bed and platen to bring them together into printing relation and to separate the same, said inking mechanism comprising rails mounted on said bed, a roller carriage reciprocably mounted on rails, an ink plate mounted on the rails, form rollers mounted on the carriage, means for reciprocating the carriage 35 on its rails alternately to engage the form rollers with a form on the bed and with said plate, a frame mounted on the roller carriage, ink distributing rollers for the form rollers mounted on said frame, the frame and ink plate being disposed at opposite sides of the form rollers and each thereof movable on their respective mountings away from said form rollers to afford access to both sides of said rollers when the carriage is positioned at the locality of said plate. 40
6. Inking mechanism for a printing press having a bed, a platen, means for relatively moving bed and platen to bring them together into printing relation and to separate them to afford access thereto, said inking mechanism comprising carriage blocks reciprocably mounted on the bed, 45 form rollers carried by the carriage blocks, an ink plate on the bed, means for reciprocating the carriage blocks to move the form rollers back and forth over said ink plate and over a form on the bed, ink distributing rollers for the form rollers, said distributing rollers being carried by said carriage blocks, mountings on each carriage block, one mounting for an end of each form roller, each mounting being individually slidably guided for adjustment on its respective carriage block, whereby its respective roller may be shifted toward or from the plane of the inking plate and, upon such adjustment thereof, will be simultaneously shifted toward or from the periphery of its respective ink distributing roller. 50
7. Inking mechanism for a printing press having a bed, a platen, means for relatively moving bed and platen to bring them together into printing relation and to separate the same, said inking mechanism comprising carriage blocks reciprocably mounted on the bed, a pair of form rollers carried by the carriage blocks, an ink plate on the bed, means for reciprocating the carriage blocks to move the form rollers back and forth over said ink plate and over a form on the bed, 55 an ink distributing roller common to said pair of form rollers, mountings on each carriage block, one mounting for an end of each form roller, the mountings on each block being oppositely guided for adjustment to shift their respective rollers toward or from the plane of the inking plate and, concurrently, toward or from the periphery of their common ink distributing roller. 60
8. Inking mechanism for a printing press having a bed, a platen, means for effecting a relative movement between bed and platen to bring them together into printing relation and to separate the same, said inking mechanism comprising an ink plate having a mounting supported on the bed, said plate being adapted to oscillate on said mounting in its own plane, a roller carriage reciprocably mounted on the bed, form rollers mounted on the carriage, means for reciprocating the carriage to engage the form rollers with a form on the bed and with the ink plate, and means for swinging the ink plate from one of its oscillatory positions to another during one cycle of the form rollers and for swinging said plate back to starting position during the following cycle of said form rollers, whereby the plate is differently angularly disposed with respect to the form rollers as they travel over said plate at different times, said mounting for said plate being hingedly supported by the bed and swingable to carry the plate out of the inking plane to give free access to said plate and to said form rollers, said plate oscillating means including a rotating member coaxially disposed with respect to the hinging axis of the mounting for said plate. 65
9. Inking mechanism for a printing press having a bed, a platen, means for relatively moving said bed and platen in a normal manner bringing the same together into impression effecting relationship upon each cycle of bed and platen and further having throw-off mechanism for affecting the operation of said means to prevent the relative positioning of bed and platen for an impression, said inking mechanism comprising an ink plate mounted on the bed to move 70 in its own plane, form rollers, means for reciprocating said rollers to engage them with a form on the bed and with the ink plate, an ink roll between the plate and form, an oscillatory mounting for the ink roll, means for oscillating 75 carriage blocks reciprocably mounted on the bed, 75

said mounting to advance the ink roll into engagement with the form rollers in their movement from the form to the plate and for retracting said mounting to carry said ink roll clear of said inking rollers upon the return of the latter from said plate to said form, means operated by said oscillating mounting for intermittently shifting the ink plate to present it in different relations with respect to said form rollers, as said rollers travel over said plate at different times, and means associated with the press throw-off mechanism for rendering said mounting oscillating means inoperative to advance the fountain when impression effecting relationship between bed and platen is prevented, whereby, in such case, inking of the form rollers and shifting of the ink plate are simultaneously avoided.

10. Inking construction for a printing press having an impression throw-off mechanism, said inking construction including form rollers, an ink plate adapted to be contacted by said form rollers and mounted for oscillating movement in its own plane, an ink roll movable into and out of contact with said form rollers, means operated normally to move the ink roll through one cycle and to swing the ink plate in one direction upon each cycle of the press, said means being rendered inoperative by the throw-off mechanism of the press to prevent the inking of the form rollers and the shifting of said plate upon each press cycle in which the impression is thrown off.

11. Inking mechanism for a printing press, said mechanism comprising blocks mounted on the press, a form roller, an ink distributing roller for said form roller, mountings, one on each block, each mounting supporting one end of the form roller, said mountings being movably guided for adjustment whereby the form roller may be moved toward or from the distributing roller and simultaneously toward or from the inking plane of the press.

12. Inking mechanism for a printing press, said mechanism comprising blocks mounted on the press, a form roller, an ink distributing roller for said form roller, cup bearings, one on each

block, each bearing removably receiving one end of the form roller, keepers releasably securing the form roller in said cup bearings, said bearings being movably guided for adjustment on said blocks, whereby the form roller may be moved toward or from the distributing roller and simultaneously toward or from the inking plane of the press.

13. Inking mechanism for a printing press having a platen, a bed, means for relatively moving said bed and platen toward and away from each other in a normal manner bringing the same together in impression effecting relationship upon each cycle of bed and platen and further having throw-off mechanism for affecting the operation of said means to prevent the relative positioning of bed and platen for an impression, said inking mechanism comprising form rollers, a movable ink fountain having a feed roll, means operating normally to move said fountain forth and back from a retracted non-inking position into an advanced inking position, wherein the fountain feed roll is positioned to be contacted by the form rollers, and means operated, when an impression between bed and platen is prevented to prevent the fountain moving means from advancing the fountain into said inking position.

14. Inking mechanism for a printing press having a platen, a bed, means for relatively moving bed and platen toward and away from each other in a normal manner bringing the same together in impression effecting relationship upon each cycle of bed and platen and further having throw-off mechanism for affecting the operation of said means to prevent the relative positioning of bed and platen for an impression, said inking mechanism comprising form rollers, a reversely movable inking roller normally advanced and retracted intermittently to contact and supply said form rollers with ink, and means operating, when an impression between bed and platen is prevented, to prevent the advancement of said inking roller and the supplying of ink thereby to said form rollers.
